US00D687975S

(12) **United States Design Patent**
Mugge et al.

(10) **Patent No.:** **US D687,975 S**
(45) **Date of Patent:** **** Aug. 13, 2013**

(54) **MOLDED SURFACE OF A CONCRETE PRODUCT**

- (71) Applicant: **Anchor Wall Systems, Inc.**,
Minnetonka, MN (US)
- (72) Inventors: **Jimmie L. Mugge**, Inver Grove Heights,
MN (US); **Robert Joel Wolter**,
Chanhassen, MN (US)
- (73) Assignee: **Anchor Wall Systems, Inc.**,
Minnetonka, MN (US)
- (**) Term: **14 Years**
- (21) Appl. No.: **29/442,131**
- (22) Filed: **Dec. 14, 2012**

(57) **CLAIM**

The ornamental design for a molded surface of a concrete product, as shown and described.

DESCRIPTION

FIG. 1 is a front view of a molded surface of a concrete product, according to our design;

FIG. 2 is a right side view thereof;

FIG. 3 is a left side view thereof;

FIG. 4 is a top view thereof;

FIG. 5 is a bottom view thereof; and,

FIG. 6 is a right perspective view thereof.

The broken lines in all views are included for the purpose of illustrating a portion of the concrete product that forms no part of the claimed design.

1 Claim, 6 Drawing Sheets

See application file for complete search history.
